UNITED STATES PATENT OFFICE.

HARLEY C. MOULTON, OF DORCHESTER, MASSACHUSETTS, ASSIGNOR TO ARBETTER FELLING MACHINE COMPANY, OF BOSTON, MASSACHUSETTS, A CORPORATION OF MAINE.

BENDER MECHANISM FOR BLINDSTITCH SEWING-MACHINES.

1,316,458.

Specification of Letters Patent. Patented Sept. 16, 1919.

Original application filed September 8, 1915, Serial No. 49,623. Divided and this application filed September 8, 1915. Serial No. 49,621.

To all whom it may concern:

Be it known that I, HARLEY C. MOULTON, a citizen of the United States, and resident of Dorchester, county of Suffolk, State of

5 Massachusetts, have invented an Improvement in Bender Mechanism for Blindstitch Sewing-Machines, of which the following description, in connection with the accompanying drawing, is a specification, like 10 characters on the drawing representing like parts.

This invention relates to improvements in bender mechanism for sewing machines and the object thereof is to produce a simplified 15 bender mechanism in which the proper alinement of the bender in respect to the stitch forming mechanism may at all times be preserved with means whereby a fine and accurate adjustment may be made of the throw 20 of the bender to accommodate the machine to different kinds and thicknesses of material.

Another object of the invention is to provide means for taking up wear between connected 25 relatively movable parts of the bender mechanism.

Another object of the invention is to simplify the bender actuating mechanism and this is accomplished in the present case by 30 providing a bender actuating cam directly engaging a member rotated with the bender, said cam being located upon a rock shaft which is actuated through the medium of a lever having universal pivotal connection, 35 power being transmitted through said lever from a lever actuated from the main shaft of the machine and connected to said transmitting lever by a universal joint.

Other objects of the invention will more 40 fully appear from the following description, the accompanying drawings, and will be pointed out in the annexed claims.

The invention is illustrated herein as embodied in a padding machine but it will be 45 understood that the principles disclosed herein may be applied to other forms of sewing machines such as felling machines and the like.

The drawings illustrate the sewing machine in a conventional manner the mechanism for actuating the stitch forming mechanism, the feeding mechanism having been

omitted since these are disclosed in assembled position in a companion application filed Sept. 8, 1915, Ser. No. 49,623, of which 55 this constitutes a division.

In the drawings;

Figure 1 is a side elevation of a sewing machine embodying my invention, a portion of the standard and arm being broken away 60 to show the connection of the bender actuating mechanism to the main shaft,

Fig. 2 is an underneath plan view of the bed plate of the machine showing the bender mechanism and the supporting frame for the 65 feed mechanism the feeding mechanism and its actuating means being omitted,

Fig. 3 is an end view of the head of the machine,

Fig. 4 is a rear sectional view on lines 4—4 70 Fig. 1,

Fig. 5 is a detail vertical sectional view through the bed, the bender guide and bearings for the cam shaft which actuates the bender, the cam shaft, cam, and bender 75 being shown in elevation,

Fig. 6 is a view of the bender fork showing an adjustable shim for taking up wear between the fork and the bender,

Fig. 7 is a vertical sectional view through 80 the bender supporting mechanism showing the bender actuating cam and rock shaft in elevation, and,

Fig. 8 is a detail sectional view of the pivotal connection between the member which 85 supports the bender actuating rock shaft and cam and the adjusting device.

The machine illustrated herein has the usual bed plate 1 and depending longitudinal flanges 2—3, a standard 4 and a forwardly extending arm 5 terminating in a head 6. A shaft 7 extending longitudinally of the arm and journaled in suitable bearings serves to actuate the stitch forming mechanism and feeding mechanism, not 90 shown, and preferably serves directly to actuate the bender mechanism in the manner hereinafter to be described. The stitch forming mechanism is conventionally illustrated herein and comprises a curved oscillating needle 8 carried by a needle bar 9 pivoted upon the stud 10 in the forked end 11 of a needle bar support, means preferably being provided for oscillating the needle 100

bar and also for vibrating the same laterally.

The head is preferably provided with an additional extension 12 forming a hook 5 bracket in which the shaft of a preferably rotating hook is mounted, the hook being actuated to coöperate properly with the needle. A presser foot 13 desirably is connected rigidly to the hook bracket 12 at its 10 lower end as is usual in blind stitch sewing machines.

Any suitable take-up and feeding mechanisms may be provided, the feeding mechanism however being preferably that illustrated in my companion application above mentioned.

The bed plate of the machine is preferably provided beneath the stitch forming mechanism with a depressed portion 14 having an 20 aperture 15 to receive a yieldable work support with the feeding mechanism operatively connected thereto as illustrated in my companion application aforesaid.

The bender 16 in the preferred embodiment of the invention illustrated herein is in the form of a flat bar which is slidably mounted in guides 17 in a bracket 18 which is provided with a flange 19 by means of which it is secured by screws or bolts 20 to the under surface of the bed 1. The bracket 17 is provided with a screw threaded aperture 21 adapted to receive an adjusting screw 22 forming the seat of a spring 23 adapted to support the outer end of a pivoted frame which is pivotally mounted in the flanges 2-3 of the bed plate and serves to support the work support and feeding mechanism in the manner disclosed in my companion application aforesaid.

40 This frame, as illustrated herein, is in the form of a skeleton structure having longitudinal sides 24-25 mounted upon pivots 26, 27 seated in the flanges 2-3 of the main frame adjacent the rear end of the sewing 45 machine, said frame being provided with transverse webs 28, 29, and 30, the web 30 having an extension which rests upon the end of the spring 23.

The bender 16, which is mounted in the 50 ways 17 in the bracket 18 is preferably provided with a lateral extension 31 which is seated in a slot 32 in a cam engaging member having a bender fork, said member being readily secured to the bender by screws 55 34-35. The bender fork is provided with flanges 36, 37 preferably at right angles to the bender adapted to be engaged by the surface of the bender actuating cam. In order to provide for adjustment to compensate for wear one of the flanges desirably is beveled on its inner face as illustrated in Fig. 6 and a shim 39 having a complementary beveled surface is adjustably secured thereto by screws 40 seated in the shim 39 60 passing through slots 41 in the flange 37.

A shim 42 (see Fig. 7) desirably may be placed alongside of the bender in its guideway in order to save the necessity of accurately machining the parts and also to provide a removable means which may be replaced to take up such wear as may occur between the bender and its guideway.

The bender is preferably actuated directly through a cam 45 mounted eccentrically upon the end of a rock shaft 46 which 70 is provided at its end with an arm 47 which is oscillated through a lever hereinafter to be described.

In order to provide for the accurate adjustment of the bender and to permit a 80 yielding movement thereto when the end of the bender encounters an obstacle the bender supporting shaft desirably is mounted in bearings in a yieldably and adjustably supported member or frame.

As illustrated herein the shaft 46 is mounted in a bushing 48 in bearings 49 in a transverse skeleton frame 50 preferably having extensions at its ends in the form of yokes. The yoke at the front end of the 90 frame is provided with bosses 51 in which is journaled a transverse pivotal shaft 52 which passes through and is secured in the lower end of a reciprocable rod 53 having a stem 54 of reduced diameter which is slidably mounted in a hollow boss 55 depending from the under surface of the bed plate. The aperture in the boss preferably extends through the bed plate of the machine and the stem 55 of the rod 53 is sufficiently reduced to permit the introduction of spring collars 56, 57. The lower collar 56 is supported in place by a plate 58 secured to the lower end of the bars 55 while the upper collar 57 is slidably mounted upon the stem 100 54 within the aperture in said boss.

A helical spring 59 surrounding the stem 54 is located between the collars 56 and 57 and the stem 54 and rod 53 are supported yieldably upon said spring by a set screw 110 60 which engages an internally threaded socket 61 in the stem 54 the head of the screw 60 being of sufficient size to rest upon the collar 57.

By the construction above described the 115 rod 53 which supports one end of the frame 50 is yieldably mounted so that the bender may yield to any obstruction. By regulating the screw 60 a greater or less tension may be placed upon the spring as may be necessitated by the character of the work. This adjustment can conveniently be made from above the bed plate of the machine by simply thrusting a screw driver into the aperture into engagement with the slot in the 125 screw 60.

The upward movement of the bender is limited by the engagement of the shoulder 53* on the rod 53 with the under face of the plate 58.

The yoke at the rearward end of the frame 50 is provided with bosses 62 by which it is secured to an adjusting screw preferably through a pivotal and sliding connection. 5 In the preferred embodiment of the invention illustrated herein the bed plate is provided with a depression 63 near its rear edge, where it is easily accessible to the operator, in which is located the head 64 of the 10 bender adjusting screw 65 which extends downwardly through a suitable aperture in the depressed portion of the bed plate and is preferably also journaled in an L-shaped bracket 66 which is secured to the under surface 15 of the bed plate. A ratchet 67 may conveniently be secured to the adjusting screw 65 by a set screw 65^x, the ratchet being located adjacent to the bracket 66 so that a pawl 68 preferably in the form of a spring 20 secured to the bracket 66 may engage the teeth of the ratchet to retain the adjusting screw 65 in any desired position.

The threaded lower end of the adjusting screw engages an internally threaded member which is pivotally and slidably connected to the bosses 62 on the yoke extending from the end of the frame 50. As illustrated herein the adjusting screw engaging member comprises a split block the portions 69—69^x 25 of which are screw threaded to engage the threads upon the adjusting screw 65. The outer sides of the portions 69—69^x are provided with horizontal preferably V-shaped grooves 70 in which slides 71 are seated. 30 Conically pointed screws 72 which are seated in the bosses 62 at the end of the yoke on the frame 50 pivotally engage the slides 71. The screws 72 may be adjusted laterally to permit the proper assembling of the parts and 35 40 may be locked in adjusted position by set nuts 73. By this construction the adjusting screw 64 may remain in vertical position while the movement of the slides 71 in the ways 70 of the blocks 69—69^x will permit 45 the slight lateral or arcuate movement due to pivotal mounting of the opposite end of the frame 50 upon the relatively stationary stud 52.

The rock shaft which carries the bender 50 actuating cam is desirably oscillated through a lever 75 which is pivotally and slidably mounted upon a stud 76 which may be anchored in a boss 77 depending from the under surface of the bed plate of the machine. 55 This pivotal bearing preferably comprises a spherical sleeve 78 bored axially to fit the stud 76, the lever 75 having a central enlargement 79 apertured to receive loosely the sleeve 78. The lever is secured to the sleeve 60 by conical pointed screws 80 the points of which enter complementary recesses in diametrically opposite portions of the sleeve 78. By this construction the lever is capable 65 not only of universal pivotal movement upon the axis of the stud 76 but also a sliding

movement longitudinally of the stud. The lever 75 is connected at its forward end to the arm 47 of the rock shaft 46 by a sliding universal joint. A preferred construction of the joint illustrated herein comprises a ball 81 carried upon the end of a rod 82 which is secured in the end of the lever 75 in any suitable manner, said ball engaging oppositely disposed spherical concaved sockets 83 in a split sleeve 84 which is slidably mounted in the cylindrical bore 85 adjacent the end of the rock shaft arm. The lever 75 is provided at its opposite end with an extension 86 having a ball 87 secured thereon, said ball engaging spherical concaved heads 88, 89 respectively of screws 90, 91 which are seated in the arms 92—93 of a lever 94 which is pivotally mounted upon a shaft 95 extending across the interior of the standard and which is provided at its upper end with a yoke 96, the arms 97—98 of which embrace a cam 99 secured upon the main shaft 7. In order to take up wear between the shaft and the yoke arms 97—98 one of the arms may be provided with a beveled surface adapted to engage a shim 100 having a beveled surface adapted to engage the beveled surface of the arm 98 meanwhile maintaining the opposite face in parallelism to the cam engaging face of the arm 97, the shim 100 may be secured to the arm 98 by large headed screws 101, 102 passing through slots in the arm 98 and seated at their ends in the shim 100.

The cam 99 is so formed and positioned upon the shaft that the bender will be actuated in properly timed relation to the stitch forming mechanism. In operation each rotation of the main shaft causes an oscillation of the lever 94 upon its pivotal shaft 95 transmitting through the universal joint at its lower end an oscillatory movement to the transmitting lever 75 which in turn oscillates the rock shaft 46 thereby oscillating the bender actuating cam 45 to raise and lower the bender.

The cams 45 and 99 are preferably so designed that the bender is given a quick raising and lowering movement with a relatively long period of dwell at both extremities of its movement, one of said dwells serving to maintain the bender in elevated position a sufficient time for the needle to penetrate and withdraw from the goods and at its lowest elevation a sufficient time to permit the full actuation of the feeding mechanism to advance the goods so that all possibility of interference between the bender and feeding mechanism will be avoided.

It will be noted that the various instrumentalities for supporting and for actuating the bender mechanism are provided throughout with means for relatively adjusting connected parts so that less care is required in constructing the apparatus than would other- 130

wise be necessary and means provided for compensating for any wear which may occur between relatively movable parts.

It will be understood that various modifications of the mechanisms herein described may be made within the scope and meaning of the claims hereto annexed.

Having thus described my invention what I claim as new and desire to secure by Letters

10 Patent is:

1. Work presenting mechanism for sewing machines comprising a reciprocable bender having a cam engaging member, a cam and cam shaft, means for yieldably supporting the same and means for actuating said cam shaft.

2. Work presenting mechanism for sewing machines comprising a reciprocable bender having a cam engaging member, a cam and cam shaft, means for yieldably and adjustably supporting the same and means for actuating said cam shaft.

3. Work presenting mechanism for sewing machines comprising a reciprocable bender 25 having a cam engaging member, a cam and cam shaft, and means for actuating the same, a supporting member for said cam shaft, means for adjustably supporting one end of said member and means for yieldably supporting the opposite end of said member.

4. Work presenting mechanism for sewing machines comprising a reciprocable bender having a cam engaging fork, a cam in said fork, a cam shaft and means for actuating 35 the same, a supporting frame for said cam shaft pivotally mounted at one end upon a yieldable support, and slidably connected at its opposite end to an adjustable support.

5. Work presenting mechanism for sewing machines comprising a reciprocable bender having a cam engaging fork, the inner wall of one arm of said fork being beveled and a coöperating shim beveled at a complementary angle slidably and adjustably secured thereto whereby the cam engaging surfaces of the fork arms may be maintained in parallelism and adjusted effectively to compensate for wear, a cam and means for actuating said cam.

50 6. Work presenting mechanism for sewing machines comprising a reciprocably mounted bender having a cam engaging member, a cam, a rock shaft connected to said cam, a lever connected to said rock shaft by a universal joint and means for actuating said lever.

7. Work presenting mechanism for sewing machines comprising a reciprocably mounted bender having a cam engaging member, a cam, a rock shaft connected to said cam, a lever mounted upon a slidable and universal pivotal support and connected to said rock shaft by a universal joint and actuating means connected to the opposite end of said lever.

8. Work presenting mechanism for sewing machines comprising a reciprocably mounted bender having a cam engaging member, a cam, a rock shaft connected to said cam, a lever mounted upon a slidable and universal pivotal support and connected to said rock shaft by a universal joint and a cam actuated lever connected to the opposite end of said lever by a universal joint.

9. Work presenting mechanism for sewing machines comprising a reciprocably mounted bender having a cam engaging member, a cam, a rock shaft connected to said cam, a lever mounted upon a slidable and universal pivotal support and connected to said rock shaft by a universal joint, an actuating lever connection to the opposite end of said lever consisting of a ball on one lever and spherically concave ball embracing members adjustably secured to the other lever.

10. In combination with work presenting mechanism for sewing machines, a power transmitting means comprising a stationary pivotal stud, a sleeve slidably and rotatably mounted thereon, a lever pivotally mounted on said sleeve, actuating means connected to one end and a work presenting instrumentality connected to the opposite end of said lever.

11. In combination with work presenting mechanism for sewing machines, a power transmitting means comprising a stationary pivotal stud, a sleeve slidably and rotatably mounted thereon, a lever having a hub embracing said sleeve and diametrically oppositely disposed adjustable conical-pointed screws pivotally engaging corresponding recesses in said hub, actuating means secured to one end of said lever by a universal connection, and means for transmitting movement to said lever actuating means.

12. In a sewing machine comprising a bed plate, a needle and complemental stitch forming mechanism, and means for actuating the same, work presenting mechanism comprising a reciprocable bender, a cam shaft, a cam for actuating the same, a supporting frame for said cam shaft, and an adjusting screw connected to said frame extending through said bed plate and operable from above the same.

13. In a sewing machine comprising a bed plate, a needle and complemental stitch forming mechanism, and means for actuating the same, work presenting mechanism comprising a reciprocable bender, a cam shaft, a cam for actuating the same, a supporting frame for said cam shaft and an adjusting screw connected to said frame extending through said bed plate and operable from above the same, and means for locking said adjusting screw consisting of a ratchet secured to said screw and a stationary pawl adapted to engage the teeth of said ratchet.

14. In a sewing machine comprising a bed plate, a needle and complemental stitch forming mechanism, and means for actuating the same, work presenting mechanism comprising a reciprocable bender, a cam shaft, a cam for actuating the same, a supporting frame for said cam shaft pivotally mounted at one end beneath said bed plate, and connected at its opposite end by a pivotal connection to an adjusting screw extending through and operable from above the bed plate.

15. In a sewing machine comprising a bed plate having a downwardly projecting boss, a needle and complemental stitch forming mechanism and means for actuating the same, work presenting mechanism including a reciprocably mounted bender, bender actuating means comprising a cam, a cam shaft and means for actuating said cam shaft, a pivotally mounted supporting frame for said cam shaft and means yieldably and reciprocably mounted in the boss in said bed plate supporting one end of said frame.

16. In a sewing machine comprising a bed plate having a downwardly projecting boss, a needle and complemental stitch forming

mechanism and means for actuating the same, work presenting mechanism including a reciprocably mounted bender, bender actuating means comprising a cam, a cam shaft and means for actuating said cam shaft, a supporting frame for said cam shaft, a rod reciprocably mounted in said boss connected to said frame and a helical spring surrounding said rod adapted yieldably to support said rod.

17. In a sewing machine comprising a bed plate having a downwardly projecting boss, a needle and complemental stitch forming mechanism and means for actuating the same, work presenting mechanism including a reciprocably mounted bender, bender actuating means comprising a cam, a cam shaft and means for actuating said cam shaft a supporting frame for said cam shaft, a rod reciprocably mounted in said boss connected to said frame and a helical spring surrounding said rod adapted yieldably to support said rod and means for varying the stress upon said spring.

In testimony whereof, I have signed my name to this specification.

HARLEY C. MOULTON.
